UNITED STATES PATENT OFFICE.

WILLIAM H. PEADEN, OF DALLAS, TEXAS.

COUNTERBALANCING AND ADJUSTABLE SASH FOR WINDOWS.

1,405,557.

Specification of Letters Patent. Patented Feb. 7, 1922.

Application filed February 5, 1921. Serial No. 442,797.

To all whom it may concern:

Be it known that I, WILLIAM H. PEADEN, a citizen of the United States, residing at Dallas, in the county of Dallas and State of Texas, have invented certain new and useful Improvements in Counterbalancing and Adjustable Sashes for Windows, of which the following is a specification reference being had to the accompanying drawings.

10 It is the purpose of the present invention to provide means on opposite sides of a window casement or frame, for not only counterbalancing the upper and lower sashes thereof, but providing means for raising one or 15 the other of the sashes, when both sashes are in lowered positions.

Another purpose consists in the provision of counterbalancing means for the upper and lower sashes of a window casement, in 20 combination with adjustable suspension means for supporting the counterbalancing connections between the upper and lower sashes, so that it is possible to hold one or 25 the other of said sashes in a lowered position, and raise the other sash by operating this suspension means.

In the application of the present invention, it is the aim to mount the counterbalancing means and the suspension means, in the parting strip between the two sashes, at the upper part of the casement, whereby access to the suspension means may be easily had from the interior of the room, for the purpose of operating the suspension means, and thereby 35 manipulating the counterbalancing connections between the sashes.

It is to be noted that the parting strip acts as such, and also constitutes a carrier for the counterbalancing connections and 40 the suspension operation means.

The counterbalancing connections and the suspension means may be mounted in the bottom of a channel member, the metal wall of which is bent to provide overlying flanges, 45 which are so spaced as to constitute a parting strip.

While the design and construction at present illustrated and set forth is deemed preferable, it is obvious that as a result of a reduction of the invention to a more practical form for commercial purposes, the invention 50 may be susceptible of changes, and the right to these changes is claimed, provided they are comprehended within the scope of what 55 is claimed.

The invention comprises further features

and combination of parts, as will be herein-after set forth, shown in the drawings and claimed.

In the drawings:

Figure 1 is a view in elevation of a window showing the application of the improved counterbalancing upper and lower sashes.

Figure 2 is a sectional view on line 2—2 of Figure 1.

Figure 3 is a sectional view on line 3—3 of Figure 2.

Figure 4 is a detail view of the tubular parting strip, which carries the hoisting or 70 raising and lowering connections for the hangers which carry the counterbalancing means.

Figure 5 is an enlarged view of the casement with its upper part and the upper 75 part of the parting strip in section, and the lower part of the casement in elevation, showing the hoisting means.

Figure 6 is a detail view of the housing with the pulleys 10 and 11 therein.

Figure 7 is a combination sectional view and elevation, showing a modified application of the invention, wherein a tubular guide is embedded in the bottoms of the channels for the sashes with the counterbalancing and hoisting means mounted therein.

Figure 8 is a sectional view on line 8—8 of Figure 7.

Referring to the drawings 1^a designates a conventional form of window casement, and 90 in the preferred form of the invention in Figures 1, 2 and 5 1 designates a hollow parting strip, which is constructed of sheet metal. This strip is inset in the wall of the casement as shown at 2, and projects sufficiently between the sashes, to act as a parting strip, for guiding the upper and lower sashes. A parting strip of this character is mounted at the upper portion of each side of the window casement, extending substantially half the height of the casement. In other words the hollow parting strip, as shown especially in Figure 5 extends from the top of the window casement or frame to the top rail of the lower sash, and does not 100 extend to the base of the casement or window frame. It is necessary to terminate or shorten this hollow parting strip midway of the casement or window frame, in order that connections of the chain with the upper 110 sash may be made. The upper part of the parting strip has a projecting part 3 pro-

vided with an opening 4, and journaled at 5 and 6 in the upper part of each parting strip are revoluble members 7 and 8, which may be in the form of gears, pulleys or the like.

Mounted to move in the channel of each parting strip is a movable hanger 9 carrying pulleys 10 and 11. A suspension guiding chain or cable, cord or the like 12 is connected to the hanger 9 as at 13, and extends through the channel of the parting strip and over the revoluble member 7, and then downwardly under the pulley 10 of the hanger, and then upwardly over the pulley 8, and passes out through the opening of the enlargement of the parting strip. When it is desired to hold the suspension cable, rope or cord in its adjusted position, the opening of one of the links of the chain 15 engages a projection 14. In order to cause the chain to engage the projection, a leaf spring 16 is attached at 15 to the enlargement of the parting strip, and has its unattached free portion forked or bifurcated, 20 so as to straddle the chain. The chain or cable in passing out through the opening of the enlargement engages between the edge of the enlargement and the leaf spring, and when the chain or rope is released from the hand of the operator, the leaf spring 25 actuates the chain, to cause the openings of any one of the links to engage the projection, thereby holding the chain in a suspended position, and in such wise that the hanger cannot drop, which would cause the upper sash to lower.

Passing over the pulley 11 of the hanger is a cable, chain or the like 17, one end of which is attached at 18 to the lower rail 40 of the lower sash 19, while the other end is attached at 20 to the lower rail of the upper sash 21. Obviously this construction is embodied on each side of the window, and furthermore it is apparent that the two sashes are counterbalanced, therefore the raising of the lower sash, will lower the upper sash and vice versa. It will also be noted that by releasing the suspension means at the top of the window on both 45 sides thereof, the upper sash may be lowered to engage the sill of the window. When the two sashes are in their lowermost positions, it is possible to hold one or the other in such position, whereby upon pulling or 50 actuating the suspension means, the other sash may be raised.

In Figure 7 the combination counterbalancing and suspension means for the two sashes of a casement are mounted in a casing 60 in the wall of the casement, and in this case, the suspension means operates over three revoluble members, such as pulleys, gears or the like 7, 7^a and 8 in an enlargement 3^a. In this construction the channels

for the suspension means and the hanger 65 are positioned at right angles to those shown in the other figures, where they are mounted in the channels of the parting strips.

Also in Figure 7, where the suspension 70 and counterbalancing means are mounted in the casing, the sheet metal of the casing is bent outwardly to provide overlying flanges, which form a parting strip between the sashes of the window. It will be noted 75 that these flanges 22 are yieldable, preventing the upper and lower sashes from binding.

The invention having been set forth, what is claimed as being useful is:

1. In a device for the purpose indicated, the combination with a guide of a window casement, of upper and lower sashes mounted in said casement, hanger means operable in the guide and having operative 85 connections with the lower rails of the upper and lower sashes, and adjustable suspension means operatively mounted in the guide and being operatively connected to the hanger, whereby the hanger may be adjusted, and thereby adjust either one of the sashes when the other is held against movement.

2. In a device for the purpose indicated, the combination with a window casement 95 having opposite guides, of upper and lower sashes mounted in the casement, movable hangers operable in the guides and having operative connections with the lower rails of both sashes, whereby the sashes counterbalance each other, and means for movably suspending said hangers.

3. In a device for the purpose indicated, the combination with a window casement having opposite guides, of upper and lower 105 sashes mounted in the casement, movable hangers operable in the guides and having operative connections with the lower rails of both sashes, whereby the sashes counterbalance each other, and means for movably suspending said hangers, and means for holding said suspending means in different 110 adjusted positions.

4. In a device for the purpose indicated, the combination with a window casement 115 having opposite guides, of upper and lower sashes mounted in the casement, movable hangers operable in the guides and having operative connections with the lower rails of both sashes, whereby the sashes counterbalance each other, and means for movably suspending said hangers, and means for holding said suspending means in different 120 adjusted positions, said holding means comprising a projection, and a leaf spring secured to each guide and straddling the first mentioned means, for automatically causing the suspension means to engage said pro-

jection to hold it in different adjusted positions.

5. The combination with a window casement having parting strips provided with 5 guide channels therein, of hangers movably suspended in said channels and having operative counterbalancing connections with the lower rails of the upper and lower sashes, and means for suspending said hangers.
- 10 6. The combination with a window casement having parting strips provided with guide channels therein, of hangers movably suspended in said channels and having operative counterbalancing connections with 15 the lower rails of the upper and lower sashes, and means for suspending said hangers, said suspending means comprising strands operatively connected to the hangers and having portions movable over the top 20 of the channels, and adapted to be actuated

for adjusting the hangers in said channels, for adjusting one or the other of the sashes.

7. The combination with a window casement having parting strips provided with 25 guide channels therein, of hangers movably suspended in said channels and having operative counterbalancing connections with the lower rails of the upper and lower sashes, and means for suspending said 30 hangers, said suspending means comprising strands operatively connected to the hangers and having portions movable over the top of the channels, and adapted to be actuated for adjusting the hangers in said channels, for adjusting one or the other of the sashes, 35 and means for holding said sash operating strands in different adjusted positions.

In testimony whereof I hereunto affix my signature.

WILLIAM H. PEADEN.
